UNITED STATES PATENT OFFICE

2,610,527

MECHANICAL TOY DRIVE

James Papay, East Chicago, Ind.

Application October 17, 1949, Serial No. 121,794

7 Claims. (Cl. 74—724)

1

This invention comprises novel and useful improvements in a mechanical toy drive and more generally pertains to a transmission gearing assembly for controlling and transmitting power in an improved manner for operating toys and the like.

The primary object of this invention is to provide an improved mechanical drive which is particularly adapted for toys of different types, and wherein power may be delivered from a power source of any desired character to various gearing assemblies to operate various devices forming parts of a toy or the like.

A further object of the invention is to provide a mechanical drive for toys which incorporate therein a novel clutch construction and clutch operating mechanism for selectively controlling the application of power from a lay shaft to various driven shafts controlling different elements of a toy.

A still further object of the invention is to provide a power take-off means for causing rotation of the toy simultaneously with operation of a driven shaft and a toy element actuated thereby.

A still further object of the invention is to provide an improved construction for journaling and supporting a lay shaft for transmitting power together with clutch element associated therewith.

These, together with various ancillary features and objects of the invention will later become apparent as the following description proceeds, are attained by the present invention, a preferred embodiment of which has been illustrated solely as an embodiment of the basic principles of the invention, in the accompanying drawings:

Figure 1 is a side elevational view, parts being broken away and shown in section, showing a toy crane embodying the principles of the invention;

Figure 2 is a top plan view of the mechanical drive disclosed in Figure 1, certain parts being omitted;

Figure 3 is a vertical longitudinal sectional view taken substantially upon the plane of the broken section line 3—3 of Figure 2;

Figure 4 is a vertical transverse sectional view taken substantially from the plane of the section line 4—4 of Figure 2;

Figure 5 is a further vertical transverse sectional view taken substantially upon the plane of the section line 5—5 of Figure 2; and

Figure 6 is a fragmentary group perspective view showing a supporting bracket and the manner in which the same rotatably but non-slidably supports a worm gear forming a part of the invention.

2

Referring now more specifically to the accompanying drawings, wherein like numerals designate similar parts throughout the various views, it should be understood that the drawings illustrating the application and principles of the invention to a rotary crane are to be regarded as illustrative only; since the mechanical drive forming a subject of this invention may be applied to numerous other uses and may be employed in various modified forms to utilize in the basic principles of the same.

In the embodiment illustrated, the numeral 10 designates a supporting base upon which may be fixedly mounted in any desired manner and in a stationary position, a horizontally disposed gear 12. A platform 14 of any desired character and which may conveniently consist of a metal plate or the like forms a base upon which the various parts of the mechanism forming this invention are mounted, this base itself being mounted in any desired manner as by a bearing assembly indicated generally by the numeral 16, see Figure 4, for rotation about the vertical axis of the gear 12 and journaled upon said gear.

In the embodiment chosen to illustrate the principles of the invention, the platform 14 has pivoted thereon as at 18, a crane or derrick boom 20, provided at its upper end with a pivot pin 22 upon which is journaled a pulley 24. Secured to the pivot 22 in any desired manner is a cable or other fastening 26 which is employed to raise or lower the boom 20 by vertically swinging the same about its pivot 18 by a mechanism to be subsequently described. A grapple indicated generally at 28 is provided with a supporting pulley 30 which is mounted upon a grapple elevating cable 32 having one end secured to the upper portion of the boom 20 as at 34 to anchor this end of the cable, this cable being then entrained over the pulley 24 and being attached to a suitable actuating means to be later set forth.

Mounted upon the supporting base of frame 14 is a housing or cab structure 36 of any convenient character, the same conveniently having anchored thereto as at 38 one end of a boom raising cable 40 which is entrained over the pulley assembly 42 secured to the end of the cable 26, the other end of the cable 40 being entrained over a guide pulley 44 mounted within the cab 36 and being attached to a suitable operating mechanism to be later set forth. It will be seen that by operation of the cable 40 the boom may be raised and lowered, and by operation of the cable 32 the grapple 28 can likewise be manipulated. It is contemplated that these two cables may be separately actuated

from a common power source by a mechanism to be now set forth.

Referring now more specifically to Figures 2-5, it will be seen that there is secured to the base member 14 a supporting frame consisting of a channel-shaped member having a base plate 46 together with parallel side walls 48 and 50. Mounted upon the base plate 46 in any desired manner is a further supporting base or frame work for receiving and mounting a prime mover together with a driving shaft connected thereto. This construction as shown in Figures 2 and 3 includes a plate 52 forming a platform upon which a reversible electric motor 54 is attached in any desired manner, the platform 52 has parallel vertical side walls 56 and 58 integrally formed thereon. The motor 54 has an armature shaft 60 extending between the side walls 56 and 58 and provided with a worm gear 62 which is constantly in mesh with a pinion gear 64 rigidly secured to a power shaft 66 which extends transversely of and is journaled in the side walls 56 and 58 in any convenient manner, this shaft being provided with a beveled driving gear 68 upon its outer end. Alternative coupling means such as spur gearing or belt and pulley drives could be employed.

The driving gear 68 is constantly in mesh with a similar bevel gear 70 which is keyed to but slidable longitudinally upon the lay shaft 72. The lay shaft 72 is journaled in laterally extending brackets forming journal bearings and which are carried by the side wall 50, these bearings being indicated at 14 and 75. It should be here noted that the lay shaft 72 which derives its power from the power shaft 66, possesses both axially slidable and rotational movement, for the purposes, as set forth hereinafter.

Journaled on the shaft 72 for rotation and relative sliding movement thereon are a pair of worm gears 78 and 80 which may be of identical construction, and which are continuously in mesh with a pair of pinions 82 and 84, respectively, which are fixedly secured to driven shafts 86 and 88 which extend transversely of and are journaled in the side walls 48 and 50 and are positioned beneath the lay shaft 72.

Rigidly secured to the shafts 86 and 88 for rotation therewith are a pair of drums 90 and 92, which, as shown in Figure 1, may be respectively connected to the cables 40 and 32 for operation of the boom and of the grapple elements.

In accordance with this invention, the worm gears 78 and 80 are maintained in axially stationary position while the lay shaft 72 is moved axially with respect to the worm gears as set forth hereinafter. To maintain these worm gears in this axially stationary position, a plurality of laterally extending brackets 94 are carried by the wall 50, and terminate in slotted or notched recesses 96, which as shown in Figure 6 are adapted to engage annular groove 98 formed upon the worm gears 78 and 80 whereby the worm gears are free to rotate but are prevented from axial sliding movement by means of these brackets 94. These annular grooves are preferably formed upon adjacent ends of the two worm gears, and the other ends of the worm gears are provided with recessed bores 100 which constitute driven jaws which are adapted to be engaged by complementary driving jaws 102 carried by discs 104 and 106 which are rigidly secured to the shaft 72 and constitute clutch elements movable therewith. The positioning of these jaws is such that the shaft 72 may be so positioned that in the event the clutch mem-

ber will engage either of the worm gears 78 and 80; or either of the clutch members 104 and 106 may be selectively engaged to thereby establish a driving engagement between the worm gears and the lay shaft.

A compression spring 108 encircles the lay shaft 72 and is disposed between the bracket 76 and the clutch member 106 to yieldingly urge the lay shaft toward the left as viewed in Figure 2 and thereby yieldingly urge the clutch member 106 into its engaged position, with the clutch member 104 being disengaged. In this position, a direct drive is now established between the motor 54, the power shaft 66, the lay shaft 72, the worm gear 80 and the pinion gear 84 driven thereby, whereby the driven shaft 88 and the drum 92 are rotated. As will be readily understood, one or both ends of the shaft 88 may extend beyond the side walls 48 and 50 and may be provided with any suitable power take-off, such as for example as the pulley 110 indicated in dotted lines in Figure 2.

Similarly, the shaft 86 may be extended beyond the side wall 48 and provided with a driving bevel gear 112 thereon which meshes with a corresponding bevel gear 114 formed upon the upper end of a vertical shaft 116, the latter, as shown in Figure 4, extending through a suitable journal bushing 118 formed on the support 14 and having a gear 120 at its lower end adapted to mesh with the stationary gear 12. Thus, when the lay shaft operates the driven shaft 86, the latter will, through the gears 120 and 12, cause rotation of the device about the stationary horizontal gear.

As will be readily understood, in order to maintain a driving connection between the driving shaft 66 and the lay shaft 72 despite the sliding movement of the latter, it is necessary that the gear 70 be mounted in an axially non-slidable position. For this purpose, the gear may be constructed similar to the worm gear 78 as shown in Figure 6, and may be held in axially stationary position by a laterally extending bracket 94 similar to the construction and operation previously described.

In order to facilitate the sliding movement of the lay shaft 72 against the opposition of the spring 108, the opposite end of this shaft has rotatably secured thereon a finger grip button or knob 122 of any desired construction. This knob permits the shaft to be forced towards the right as viewed in Figures 2 and 3 against the resistance of the spring 108, to thereby disengage the clutch 106 and even position the shaft in neutral position with neither clutch 104 nor 106 engaged; or to cause engagement of clutch 104.

In order to reverse the operation of any of the mechanisms controlled by the gearing assembly, it is merely necessary to reverse the direction of rotation of the reversible motor 54, whereupon the lay shaft and its associated elements will be driven in the reverse direction.

It should be here noted that the series of worm and pinion gear drives are in themselves irreversible and constitute brakes thus preventing undesired reverse operation of the mechanisms driven thereby. In particular, since the worm gears 78 and 80 are restrained against axial movement, the drums 90 and 92 driven thereby and consequently the boom and the grapple actuated therefrom may be readily locked in any desired position, so that when the lay shaft 72 is in neutral position with neither clutch engaged, there will be no undesired reverse actuation of any of the driven mechanisms.

It is contemplated that the mechanism may be conveniently powered by the reversible electric motor 54; but it is also possible to operate the same manually as for example, by a manual crank 124 which is secured to the end of the lay shaft 72. Further, the electric motor 54 could be replaced by a spring motor or any other desired power source.

It should be noted that the drums 90 and 92 could be replaced by gears, pulleys or any other operating means whereby various toys or elements of toys can be controllably actuated. In addition, the shafts 86 and 88 could be provided with traction wheels whereby the mechanism could be employed to operate toy trains, trucks or tractors as desired.

From the foregoing, the construction and operation of the device will be readily understood and further explanation is believed to be unnecessary. However, since numerous modifications and changes will readily occur to those skilled in the art after a consideration of the foregoing specification and accompanying drawings, it is not desired to limit the invention to the exact construction shown and described. Accordingly, all suitable modifications and equivalents may be resorted to, falling within the scope of the appended claims.

Having described the invention, what is claimed as new is:

1. A drive mechanism for toys comprising a lay shaft having means journaling the same for rotary and sliding movement, means for rotating said lay shaft, a pair of driven shafts angularly disposed to said lay shaft, driven pinions secured to said driven shafts and driving worms freely rotatable on said lay shaft and meshing with said pinions, clutch means responsive to opposite sliding movements of said lay shaft for alternately operating said clutches and operatively connecting said worm to said lay shaft.

2. The combination of claim 1, including a spring yieldingly urging said lay shaft into position for engaging one of said clutches and a rotatable head on said lay shaft for moving the latter into the other direction for engaging the other clutch.

3. The combination of claim 1, including a spring yieldingly urging said lay shaft into position for engaging one of said clutches and a rotatable head on said lay shaft for moving the latter into the other direction for engaging the other clutch, said rotating means including a driven gear slidably but non-rotatably mounted on said lay shaft, a driving shaft having a driving gear connected to said driven gear.

4. The combination of claim 1, including a spring yieldingly urging said lay shaft into position for engaging one of said clutches and a rotatable head on said lay shaft for moving the latter into the other direction for engaging the other clutch, said rotating means including a driven gear slidably but non-rotatably mounted on said lay shaft, a driving shaft having a driving gear connected to said driven gear, a pinion on said driving shaft and a power operated worm meshing with said last pinion.

5. The combination of claim 1, including a frame, journals on said frame supporting said lay shaft, brackets carried by said frame, annular grooves in said worm, said brackets having forks rotatably engaging said grooves.

6. The combination of claim 1, including a frame, journals on said frame supporting said lay shaft, brackets carried by said frame, annular grooves in said worm, said brackets having forks rotatably engaging said grooves, said clutch means including collars having driving jaws rigidly secured to said lay shaft, complementary jaws on said collars and worms.

7. The combination of claim 1, including a frame, journals on said frame supporting said lay shaft, brackets carried by said frame, annular grooves in said worm, said brackets having forks rotatably engaging said grooves, a vertical shaft journaled on said frame and geared to one of said driven shafts, a stationary gear, means pivotally mounting said frame for rotation about the axis of said stationary gear and a gear on said vertical shaft meshing with said stationary gear.

JAMES PAPAY.
